UNITED STATES PATENT OFFICE.

OLLIE T. NELSON, OF WAUKEGAN, ILLINOIS.

MANHOLE CONSTRUCTION.

Application filed February 28, 1924. Serial No. 695,799.

This invention relates to an improvement in manhole constructions, and is particularly designed for use with boiler shells and the shells or heads of tanks where the boilers or tanks are electrically welded.

The object of the invention is to provide a manhole construction of this character which is adaptable for setting into or for organization with flat, cylindrical, spherical, curved, or irregular surfaces without any changes in the essential features of the manhole construction and wherein the parts of the manhole construction which are required to be secured together or to the shell 10 of the boiler or tank are united by electric welds.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a plan view, showing the preferred embodiment of the invention;

Figure 2 is a view in vertical section, on line 2—2 of Figure 1; and

Figure 3 is a view in end elevation.

Referring to the drawings wherein for the sake of illustration is shown one embodiment of the invention, the numeral 10 designates the shell of a boiler, tank or the like. A hole or opening 11 of proper size and shape is cut in the shell 10 and in this embodiment of the invention is shown as being of elliptical form.

An internal manhole band, designated generally at 12, is provided. This manhole ring 12 is constructed of a single piece of metal, such as steel, which is formed to the correct shape and which has its ends welded together, as indicated at 13, in Figure 1. In this embodiment of the invention, the band 12 is of elliptical form but it is to be understood that this band like the opening 11 may be made of any suitable form and size. The band 12 is snugly fitted in the opening 11 and the outer periphery of the band is welded, as at 14, to that portion of the shell 10 which defines the opening 11. With this arrangement one end of the band 12 is disposed within the shell 10 and the other

end of the band is disposed without the shell. The end of the band 12 disposed within the shell is designated at 15 and is machined for coaction with a gasket 16 to provide a packed joint as will presently appear.

A manhole cover 17 is applied to the inner end of the band 12 and the marginal portion of the cover 17 engages the gasket 16 to provide the joint hereinabove referred to. A guide flange 18 of angular form in cross section is welded to the cover 17 and coacts with the band 12.

Releasable means is provided for holding the cover 17 in position and this means preferably coacts with the cover 17 and with the outer end of the band 12 for this purpose. This releasable means includes a socket 20 welded to the cover 17 and having a slot designated generally at 21 in the top thereof, the slot 21 having an enlarged central portion 22 and narrow branches 23. A manhole crab 24 spans the outer end of the band 12. A bolt 25 is provided and has a head 26 which may be inserted through the large central portion 22 of the slot 21 and then slid into position below the portions of the top of the socket 20 which define the narrow branches 23 of the slots 21, the head 26 engaging such portions of the top of the socket as shown in Figure 2. The shank 27 of the bolt 25 extends through an opening provided therefore in the crab 24 and projects beyond the upper end of the crab. A nut 28 is threaded on the upper end of the shank 27 of the bolt 25 and coacts with the crab 24 to draw the bolt 25 upwardly and consequently to urge the cover 17 tightly against the gasket 16 which is fitted between the cover and the inner end of the band 12.

Preferably a washer 29 is interposed between the nut 28 and the crab 24. With this arrangement when the nut 28 is loosened the bolt 25 may be disengaged from the socket 20 and the cover 17 removed from the manhole. The socket 20 affords a means for manipulating the cover when removing and placing the same in position.

It will now be understood that the parts of the manhole construction which are to be secured to each other or which are to be secured to the shell of the boiler or tank are united by electric welds in a novel and effective manner. Moreover the manhole

construction is adaptable for organization with flat, cylindrical, spherical, curved, or irregular surfaces without any changes in the essential features of its construction.

5. I claim:

1. In a device of the character described, a shell having an opening longer than it is wide, an internal manhole band constituted of a single piece of metal bent to fit in said opening, said band being shaped to completely fill said opening at its periphery, the ends of the shaped band being then welded together, a weld between the outer periphery of the band and the wall of the opening or shell, said band and peripheral weld being of such strength and size as to reinforce the shell to the extent necessary to compensate for the metal cut-away from the shell to form the opening therein, a manhole cover applied to the inner edge of the band, and means cooperable with the cover and span-

ning and engaging the outer end of the band for holding the cover in position.

2. In a device of the character described, a shell having an opening longer than it is wide, an internal manhole band constituted of a single piece of metal bent to fit the opening and shaped therein, a weld between the ends of the shaped piece of metal, and a weld between the outer periphery of the band and the wall of the opening of the shell.

3. A method of making manholes consisting in providing an opening in a sheet of metal, taking a single piece of metal to form a band, bending said piece and fitting it within said opening to form a split band, welding the ends together, and welding the periphery of said band to the periphery of said opening.

OLLIE T. NELSON.
